UNITED STATES PATENT OFFICE.

FREDERICK A. PRESTON, OF HIGHLAND PARK, ILLINOIS, ASSIGNOR TO THE E. & M. CO., OF CHICAGO, ILLINOIS, A CORPORATION OF ILLINOIS.

ANTICREEPER.

1,219,772.

Specification of Letters Patent. Patented Mar. 20, 1917.

Application filed June 16, 1916. Serial No. 103,968.

To all whom it may concern:

Be it known that I, FREDERICK A. PRESTON, a citizen of the United States, residing at Highland Park, in the county of 5 Lake and State of Illinois, have invented a certain new and useful Improvement in Anticreepers, of which the following is a full, clear, concise, and exact description.

This invention relates to improvements in 10 anti-creepers or rail anchors of one-piece construction.

The objects of the invention are: to provide a rail anchor which may be readily applied to the rail base and which maintains a 15 firm frictional engagement therewith under all conditions; to provide a rail anchor of this type which resists creeping in both directions; and to provide a rail anchor which may be economically manufactured. Other 20 objects and advantages will be apparent from the following description.

In the accompanying drawings I have illustrated one embodiment of the invention, which will serve to illustrate the main features thereof. Other forms of the invention may be devised however and therefore I do not necessarily limit myself to the various details of the present disclosure.

Figure 1 of the drawings illustrates a top 30 plan view of the anchor.

Fig. 2 is a rear elevation thereof.

Fig. 3 illustrates the manner of applying the anchor to the rail base; and

Fig. 4 is a development of the blank from 35 which the anchor is formed.

The rail anchor is formed preferably from a blank of high carbon steel 1, which blank has the form of a strip or bar provided with a lateral projection 2. This projection is bent downwardly to form a tie-abutting flange. One end of the bar is bent around to form a jaw 3 which conforms in general to the cross sectional outline of the adjacent portion of the rail base. The other 45 end of said bar is bent to form a hook 4, the end of the hook having preferably a notch 5 therein. Said bar is also bent downwardly adjacent to the flange 2, as shown in Fig. 3.

50 The anchor is applied to the rail base by first hooking the jaw 3 over one side of said base, and forcing said jaw firmly against the side of said base. The angle of the jaw is normally smaller than the corre-

sponding angle of the rail base, as indicated 55 by the dotted line in Fig. 3. As a result said jaw is sprung when forced onto the rail base, whereby the anchor in final position maintains a firm frictional hold on said rail base. After forcing the jaw 3 onto one side 60 of the rail base, the other side of the anchor, which inclines downwardly, is forced upwardly by means of a suitable tool, such as a lining bar 6. The hook 4 is so shaped as to draw the jaw 3 firmly against the opposite 65 side of the rail in case it has sprung away somewhat. During this upward movement, the downwardly inclined end of said hook is bent back more nearly vertical, as it is crowded past the side of the rail. When 70 the side of the rail anchor has been lifted high enough so that the main body of the cross bar 1 is substantially in contact with the bottom of the rail base, the projecting end of the hook 4 snaps over the edge of the 75 rail base, the latter engaging within the notch 5. The rail anchor is thus prevented from springing downwardly or sidewise, and is under tension in both a horizontal and vertical direction. Therefore it maintains 80 a firm frictional hold on the rail base. The tie-abutting flange 2 is located directly beneath the jaw 3, for the reason that said jaw is intended to resist the major portion of the creeping thrust by virtue of the powerful 85 clamping action which it exerts on the rail base. Said flange is therefore located in such position as to transmit the creeping thrust directly to the cross tie 7, and it also serves to stiffen the jaw. The function 90 of the hook 4 is largely to maintain the jaw 3 in proper position on the rail base and to keep it sprung, whereby it may not only maintain the necessary vertical grip thereon but may exert a powerful lateral pressure as 95 well. Said hook also keeps the main body of the cross bar sprung by holding it against the rail. If the rail moves rearwardly, the tie-abutting flange engages the ballast and resists creeping in this direction 100 also. If the ballast is frozen, creeping may be substantially prevented.

With the construction illustrated, it will be seen that the anchor remains tight under all conditions, as rearward movement of the rail cannot operate to loosen it, due to the effectiveness of its initial grip on the rail base.

Having thus described my invention, what I claim as new and desire to secure by Letters Patent of the United States is:

1. An anti-creeper comprising a spring steel member having a jaw at one end and a hook at the other end, the extreme end of said hook engaging the upper edge of the rail base.
2. A rail anchor comprising a spring steel member having a jaw at one end which maintains a firm frictional engagement on the rail base, and having a hook at the other end, the extremity of which engages the upper edge of said rail base, said extremity having a notch which prevents lateral displacement of said anchor.
3. A rail anchor having an integral jaw at one side and having a hook at the other side thereof provided with a notch to fit the edge of the rail base, and a tie-abutting flange intermediate said parts all of which are integrally formed of spring steel.
4. A rail anchor comprising a steel bar having a jaw at one end bent to an angle somewhat less than that of the rail base section, a tie-abutting flange at the end near said jaw, said bar being bent downwardly near said jaw, and a hook at the opposite end arranged to be sprung upwardly against the other side of the rail base.
5. A rail anchor comprising a transverse member beneath the rail base having one end bent to form a jaw smaller than the rail base section whereby said jaw is sprung when in place and exerts a powerful vertical grip thereon, a tie-abutting portion adjacent to said jaw to stiffen the latter and

transmit the creeping thrust without skewing the anchor appreciably, and means at the other end of said transverse member for insuring a powerful lateral grip of said jaw on the rail base.

6. A rail anchor comprising a transverse member beneath the rail base having one end bent to form a jaw smaller than the rail base section, whereby said jaw is sprung when positioned on said rail base, a hook at the other end of said transverse member, and a tie-abutting flange directly beneath said jaw, the portion of said transverse member between said hook and said flange being bent downwardly away from the rail base, and the end of said hook normally obstructing the raising of the adjacent end of said transverse member, whereby said hook has to be forcibly sprung over the rail base, thereby drawing said jaw laterally against the opposite side of the rail base and putting said transverse member under tension beneath the rail base.

7. A rail anchor comprising a transverse member beneath the rail base provided with a jaw at one end which is smaller than the rail base section, whereby the jaw is sprung when in place and exerts a powerful grip thereon, means for gripping the rail at the other end of said transverse member, and a tie-abutting projection positioned intermediate said ends and near said first-named jaw.

In witness whereof, I hereunto subscribe my name this 6th day of June, A. D. 1916.

FREDERICK A. PRESTON.
